UNITED STATES PATENT OFFICE.

ALPHONSE A. SEBASTIAN, OF CHICAGO, ILLINOIS, ASSIGNOR TO ANDREW HOFFMAN MFG. CO., OF CHICAGO, ILLINOIS, A CORPORATION OF ILLINOIS.

CEILING LIGHT.

Application filed January 6, 1923. Serial No. 611,194.

To all whom it may concern:

Be it known that I, ALPHONSE A. SEBASTIAN, a citizen of the United States, residing at Chicago, in the county of Cook and State of Illinois, have invented certain new and useful Improvements in Ceiling Lights, of which the following is a specification.

The present invention relates to ceiling light constructions, and has for its principal object the provision of a ceiling light which is characterized by certain novel improvements in the arrangement, mounting and operation of the movable sash portion.

While the foregoing statement is indicative, in a general way, of the nature of the present invention, various advantageous features not specifically referred to in this disclosure will be obvious upon a full understanding of the structure as set forth in the following description and accompanying drawings, wherein is delineated a preferred embodiment of the invention. It will be understood, however, that this particular embodiment is chosen primarily for the purpose of exemplification, and is not intended to restrict in any way the spirit of the invention or to limit unnecessarily the scope of the appended claims.

In the drawings—

Fig. 1 is a plan view of the ceiling light with the stiles sectioned and certain portions of the suspending devices removed;

Fig. 2 is a sectional view of the same in a partly open position; and

Fig. 3 is an end elevation of the same showing the horizontal guides and the supporting frame in section.

Referring now with more detail to the drawings, it will be observed that the ceiling light construction consists principally of a supporting frame 10, two movable sashes 11 and 12, and means 13 adapted, during the movement of the sashes, to guide the same in a manner characteristic of this invention.

The frame 10 is of rectangular form and is mounted horizontally in an aperture of a ceiling 14 with the lower edge of the frame flush with the ceiling and finished off with the usual trim 15. The frame is provided, around the lower portion of its inner periphery, with an auxiliary frame and bead-

ing 16 which provides a continuous supporting shoulder 17 for the sashes when in their closed position. The frame is also provided, intermediate its length, with two spaced stiles 18 and 19 which extend upwardly from the middle points of the frame sides 20.

The movable sashes 11 and 12 are of equal size, and substantially fill the opening in the frame 10 and overlie the beading 16 when arranged edge to edge in their closed position of peripheral support on shoulder 17 of the frame. The meeting edges of the sashes are provided with offset complementary tongues 21 which join to produce a close fit of the sashes when in their closed position.

The guide means 13 consist of two spaced horizontal guide channels 22 positioned upon the shoulder 17 against the frame sides 20, and one vertical guide channel 23 extending perpendicularly upwards from one of the guide channels 22 and positioned against the inner face of the stile 19. The guide channels referred to are each preferably rectangular in cross-section and formed with three closed sides and one centrally slotted side, whereby to provide enclosed roller tracks having openings for the passage thereto of the roller axles. The ends of the sashes opposite to the interfitting ends are rounded off along their lower edges 24 for the purpose hereinafter apparent and are provided adjacent their extremities with brackets 25 in which are mounted aligned axles 26 carrying rollers 27. The axles 26 extend horizontally through the slots in the channels 22 and the rollers 27 are contained within the channels, as shown in Fig. 3. The interfitting ends of the sashes are hinged together along their lower edges with two or more spaced hinges 28, and are provided adjacent corresponding edges of their upper surface with a spanning hinge bracket 29 composed of two sash attached leaves 30 and two movable leaves 31 hinged together and to the leaves 30. The pin 33 hinging the two movable leaves 31 together is extended laterally into the slot in the vertical channel 23 and is there provided with a roller 34. The pin 33 has attached thereto, between the bracket 29 and the channel 23, a

coupling hook 35, which is removably secured to a complementary ring member 36 carried by the lower end of a supporting tape 37. The tape 37 operates on the reel 5 38 of a spring balanced device 39 secured to the stile 19, and serves to maintain the sashes in a state of equilibrium in either a partly or fully open position of the same. The interfitting ends of the sashes are also 10 provided, adjacent the edges of their upper surfaces opposite to the hinge bracket 29, with a yoke 40 composed preferably of two short ends of chain which are attached to the sashes at spaced corresponding points 15 and connected together with an S-link 41. This yoke in turn is connected with a spring balance device 42 which is secured to the stile 18 and provided with a tape 43 and ring member 44 in the manner of the device 39.

The ceiling light is operated to assume either a partly or fully open position by the application of pressure to its under side at any point adjacent to the hinged portions 25 of the sashes. The sashes being counter-weighted as described, it will be understood that very little pressure is required in the operation. As the hinged portions of the sashes are raised, being guided vertically by 30 the roller 34 in the guide channel 23, the free ends of the sashes approach each other, being guided in a common plane of the frame by the rollers 27 in the guide channels 22, and the two sashes assume an angular inverted V-shaped position. The sashes will 35 remain in any partly open position in which placed and may be moved, if desired, to a fully open position wherein the sashes are substantially folded together in a vertical position.

The guide channel 23 is provided with a plurality of small transverse apertures 45 adjacent its upper extremity through any one of which the pin 46 may be inserted for 45 the purpose of limiting, as may be desired, the extent to which the sashes will normally open. The upper extremity of the channel 23 is open, and is lower than the height that the roller 34 will assume when the sashes 50 are folded together in their fully open position; in which position the roller will leave the channel 23, and the supporting tapes may then be disengaged from the sashes and the sashes moved bodily to either end 55 of the frame, as shown by dotted lines in Fig. 2.

In order to compensate for structural irregularities in the spacing of the horizontal guide channels 22, or warping of the supporting frame or the sashes, the axle pins of the rollers 27 and 34 may be adapted for lengthwise movement in their sockets in the brackets 25 and 29, or may be provided with conical heads adapted to interfit with similarly shaped central apertures in the

rollers. This construction of the pin heads and rollers is indicated in dotted lines in Fig. 3, and forms the subject-matter of a separate co-pending application.

I claim:

1. In a ceiling light, a frame, two hinged sashes adapted to extend horizontally in the frame when in their closed position, means adapted to guide the free ends of the sashes horizontally in the frame when the hinged ends of the sashes are moved vertically to fold the sashes together in their open position, and a vertically extending guide associated with the frame for directing the hinged ends of the sashes in their vertical movement. 70

2. In a ceiling light, a frame, two hinged sashes adapted to extend horizontally in the frame when in their closed position, means adapted to guide the free ends of the sashes horizontally in the frame when the hinged ends of the sashes are moved vertically to fold the sashes together in their open position, and counter-balancing means acting on the sashes in opposition to the action of gravity on the same whereby to maintain the sashes in equilibrium in any position which the same may be caused to assume. 85

3. In a ceiling light, a frame, two hinged sashes adapted to extend horizontally in the frame when in their closed position, rollers on the free ends of the sashes, guides on the frame adapted to receive the rollers and thereby guide the free ends of the sashes horizontally in the frame when the hinged ends of the sashes are moved vertically to fold the sashes together in their open position, and means acting on the hinged ends of the sashes in opposition to the action of gravity on the same whereby to maintain the sashes in any position which the same may be caused to assume. 90

4. In a ceiling light, a frame, two hinged sashes associated with the frame, and means adapted to guide the hinged ends of the sashes in a direction perpendicular to the plane of the frame whereby the two sashes may be folded together, said means being adapted to permit the sashes to be released from such guide engagement in the folded position of the same whereby the two sashes may be moved in unison parallel to the plane of the frame. 100

5. In a ceiling light, a frame, two hinged sashes adapted to extend horizontally in the frame when in their closed position, rollers on the free ends of the sashes, guides on the frame adapted to receive the rollers and thereby guide the free ends of the sashes horizontally in the frame when the hinged ends of the sashes are moved vertically to fold the sashes together in their open position, a roller adjacent the hinged ends of the sashes, a guide extending vertically from the frame and adapted to receive the roller 115 120 125 130

and thereby guide the hinged ends of the sashes vertically from the frame, said vertically extending guide terminating short of the uppermost position of its associated roller whereby the roller will leave the guide in its uppermost position and the sashes will be released from such guided engage-

ment in the folded position of the same and may be moved in unison to either end of the frame.

10

In testimony whereof I have hereunto subscribed my name.

ALPHONSE A. SEBASTIAN.
